UNITED STATES PATENT OFFICE.

JOHN H. KATE, OF DES MOINES, IOWA, ASSIGNOR OF ONE-HALF TO ED. J. RAYMOND, OF DES MOINES, IOWA.

WATER-TRAY FOR INCUBATORS.

1,155,819.

Specification of Letters Patent.

Patented Oct. 5, 1915.

Application filed April 13, 1914. Serial No. 831,546.

To all whom it may concern:

Be it known that I, JOHN H. KATE, a citizen of the United States, residing in Des Moines, county of Polk, and State of Iowa, 5 have invented a new and useful Improvement in Water-Trays for Incubators, of which the following is a specification.

The object of this invention is to provide improved means in an incubator for containing water to supply moisture to the contents 10 of said incubator during the process of incubation.

A further object of this invention is to provide an improved water tray adapted to 15 be removably mounted in an incubator.

My invention consists in the construction, arrangement and combination of elements hereinafter set forth, pointed out in my 20 claims and illustrated by the accompanying drawing, in which—

Figure I is a plan illustrating my improved device mounted in position for use. Fig. II is a vertical section of the same. Fig. III is a perspective of the same.

25 In the drawings herewith a portion only of an incubator of common type is shown, in which the numeral 10 designates generally a lamp chimney mounted in a cylindrical support 11 and surrounded by a guard or shield 12, usually of sheet metal. A bed or tray 13 covered with wire mesh surrounds the cylindrical support 11 and is adapted to receive eggs to be incubated. A cap or deflector 14 is mounted removably on the upper end of 30 the lamp chimney 10 and is designed to spread and deflect heat from said lamp chimney, and is also provided with tubes or pipes 15 adapted to lead some of the heat to different portions of the incubator.

40 The numeral 16 designates generally a wafer of common form adapted to be acted upon and expanded by the heat from the lamp chimney to the end of regulating and controlling the temperature of the interior 45 of the incubator, through a lever 17 leading to and designed to operate devices (not shown) of common form adapted to admit atmospheric air to the incubator.

50 My improvement consists of a tray or receptacle removably mounted on the cylindrical support 11 adjacent the lamp chimney 10 and designed to contain water. This tray or receptacle preferably is of sheet metal and is generally circular in plan view. 55 It is formed with a bottom 18 and an in-

tegral outer rim or side wall 19 rising from the outer margin thereof. The bottom 18 is formed with a central opening of circular form to receive the lamp chimney 10 and shield or guard 12, and said opening is surrounded in part by an inner rim or side wall 20 concentric with the outer wall 19. The bottom 18 also is formed with an opening at one side and leading from the central opening to the circumference of said bottom, and supplied with radial side walls 21, 22 connecting the outer side wall 19 and inner side wall 20. This lateral opening in the bottom is for the purpose of receiving and permitting free and unrestricted operation of the 60 lever 17 and thermostat devices.

The tray or receptacle so described is mounted loosely on the top of the cylindrical support 11, by removal of the cap or deflector 14, and is supplied with water. This 75 water is evaporated by the heat of the lamp chimney 10 and moisture is supplied to the eggs under process of incubation, it being a well known fact that it is desirable to supply a certain amount of moisture during such 80 process.

I claim as my invention—

1. In an incubator having a cylindrical support, a lamp chimney disposed in the cylindrical support and extending thereabove, a water tray mounted on the cylindrical support and provided with an enlarged central opening, and a guard surrounding the chimney and extending partially within the central opening of the water tray. 90

2. In an incubator having a cylindrical support, a lamp chimney disposed in the cylindrical support and extending thereabove, a water tray having a central opening removably receiving the lamp chimney, the latter extending above the tray, and a deflector removably supported on the extended portion of the chimney above the water tray for spreading the heat thereover. 95

3. In an incubator having a cylindrical support and a lamp chimney therein and also a thermostat lever adjacent said lamp chimney, a water tray mounted on said cylindrical support and formed with a central opening for the projecting portion of said lamp chimney, said tray also being formed with a lateral opening for said lever. 100

4. In an incubator having a cylindrical support and a lamp chimney therein and also having a thermostat lever adjacent said 110

lamp chimney, a water tray adapted to be mounted on said cylindrical support, said tray comprising a bottom formed with a central opening to receive said lamp chimney, 5 an outer side wall on said bottom, an inner side wall surrounding said central opening, said bottom also being formed with a lateral opening to receive said thermostat lever, said

lateral opening leading to the central opening, and side walls for said lateral opening and connecting the inner and outer side walls.

JOHN H. KATE.
